UNITED STATES PATENT OFFICE.

PETER BUCHER, OF MANNHEIM, GERMANY.

ACETYLENE-GAS-GENERATING APPARATUS.

SPECIFICATION forming part of Letters Patent No. 700,405, dated May 20, 1902.

Application filed May 9, 1900. Serial No. 16,109. (No model.)

To all whom it may concern:

Be it known that I, PETER BUCHER, a subject of the Emperor of Germany, and a resident of Mannheim, Germany, have invented 55
certain new and useful Improvements in Acetylene-Generating Apparatus, of which the following is a specification.

My present invention relates to acetylene-generating apparatus, the object being to provide 10 an automatically-operating apparatus of this kind; and it consists in mechanism constructed and combined as hereinafter fully described.

In the accompanying drawings, Figure 1 is 15 a transverse section of apparatus embodying my invention. Fig. 2 is a section at right angles to that of Fig. 1 and taken in front of the carbid-holders. Fig. 3 is a detail in perspective view of the disengaging shaft engaged 20 with certain of the carrying-levers for the carbid-holders.

Referring to the drawings, *a* represents a water-tank, having an inclined partition *b* extending from the casing above fluid-level to 25 a point therebelow and forming the gas-chamber *c*. Opening into the latter is a gas-pipe *d*, extending downward therefrom and through the wall of the tank *a*, said pipe serving to lead acetylene-gas from the chamber to a 30 range of jets or a holder. Another pipe *d'* leads gas to the gas-holder *B*.

In the side walls of the tank *a* is journaled a horizontal shaft *e*, supporting rigidly a suitable restoring rod or bar *f*, extending below 35 the shaft as a loop or bridge from one side of the tank to the other for the purpose herein-after described, and a loosely-mounted series of carriers *h' h² h³ h⁴ h⁵*, &c., serving to receive the carbid-holders *g' g² g³ g⁴ g⁵*, &c. At 40 the top of the tank *a* is journaled another shaft *i*, provided with catches *k' k² k³ k⁴ k⁵*, &c., which are longer or shorter in accordance with the distance to which the shaft *i* has to be rocked from normal to disengage 45 them and which are preferably arranged on a helicoidal line. Said catches engage holes *l*, provided at the upper end of the carriers *h' h²*, &c., and retain said carriers elevated so long as they are engaged.

50 The operation of the automatic acetylene-generating apparatus is as follows: When the carriers *h' h²*, &c., are turned up against the

partition *b*, the shaft *i*, with its catches *k' k²*, &c., is turned toward the front, so that the latter engage the respective holes *l* in said carriers to hold the latter. Then the carbid-holders *g' g²*, &c., being filled, are suitably secured—for instance, by means of clips *m²* on the carriers *h' h²*, &c.—so that the center of gravity of said carbid-holders is at some distance in front of the axis of the shaft *e*. Said carbid-holders may be perforated or of any suitable construction, as shown, and they have an end gate sliding in ways or grooves for the insertion of carbid. If it is desired to start 60 the apparatus, the catch *k'* is disengaged by hand, whereupon the carrier *h'* and its carbid-holder *g'* swing over and downwardly, as indicated in dotted lines, into the tank *a* and under the partition or hood *b*, where acetylene-gas is generated. Said acetylene-gas flows through the pipe *d* to burners or through the pipe *d'* into the gas-holder *B*, which rises correspondingly. As the acetylene-gas is consumed the gas-holder is lowered, and this movement is transmitted to the shaft *i* through 70 the agency of a chain or stop or any suitable device and the crank-arm *n* secured on said shaft, whereby the latter is rotated in accordance with the lowering of the gas-holder 75 and operates to disengage the second catch *k²*, and therefore the carbid-holder carrier *h²*, whereby the second carbid-holder *g²* drops by the action of its own weight into the tank *a*. This is repeated until all the carbid-holders 80 are dropped into the tank. A simple means to this end is the chain *O*, attached at one end to the crown of the gas-holder, thence passing over pulley *R* on fixed overhead frame *r*, then down through the outer end of 85 lever *n*, and provided with a weight *o* a suitable distance therebeneath. As gas is drawn off and the gas-holder sinks the weight will be drawn up until it strikes the lever and rocks it sufficiently to disengage the first 90 catch. The next time the holder sinks it will go a little farther, lifting the weight against the lever far enough to disengage the second catch, and so on, sinking farther and farther each successive time.

For removing the carbid-holders from the tank *a* all that is necessary to do is to rotate the shaft *e* in a direction opposite to that of the down movement of the carbid-holders,

which may be effected by means of the crank *m*, secured to said shaft. The levers *h' h²*, &c., resting on the restoring arm or rod *f*, fast on the shaft *e*, are thus raised, together with 5 the carbid-holders, which may then be refilled or replaced by others.

Having fully described my invention, what I claim, and desire to secure by Letters Patent, is—

- 10 1. In the improved acetylene-gas-generating apparatus, the combination with a water-tank and a shaft journaled in walls of said tank, of a series of carriers loosely mounted on said shaft, having holes in their upper 15 ends and adapted to receive a series of interchangeable carbid-holders, another shaft journaled above the first-mentioned shaft, a series of suitable catches on the upper shaft arranged to engage the holes in said carriers 20 and to be successively disengaged therefrom by the rocking of said shaft, means for actuating the upper shaft during the down movement of the gas-holder, and means for raising the carbid-holders after the operation, 25 substantially as set forth.

2. In the improved acetylene-gas-generating apparatus, the combination with a water-tank and an inclined partition extending downwardly from the top of said tank and forming a gas-collecting hood, of a shaft journaled in the walls of the latter, a series of carriers loosely mounted on said shaft, having holes in their upper ends and adapted to receive carbid-holders, a second shaft journaled above the partition, a series of curved 30 catches progressively increasing in length and arranged on said upper shaft and engaging the holes in the loosely-mounted levers, a bridged restoring-rod secured on the first-mentioned shaft and upon which drop the levers in operation, means for rotating the lever-carrying shaft, and means for transmitting the down movement of the gas-holder to the upper shaft, substantially as set forth. 35

In testimony whereof I have hereunto set 40 my hand in presence of two witnesses.

PETER BUCHER.
